UNITED STATES PATENT OFFICE.

HARRISON H. BOYCE, OF FOREST HILLS, NEW YORK.

TEMPERATURE-INDICATING SYSTEM AND APPARATUS FOR INTERNAL-COMBUSTION ENGINES.

1,206,783.

Specification of Letters Patent. Patented Nov. 28, 1916.

Original application filed June 20, 1914, Serial No. 846,247. Divided and this application filed August 30, 1916. Serial No. 117,595.

To all whom it may concern:

Be it known that I, HARRISON H. BOYCE, a citizen of the United States, residing at Forest Hills, in the county of Queens and State of New York, have invented certain new and useful Improvements in Temperature-Indicating Systems and Apparatus for Internal-Combustion Engines, of which the following is a specification.

10 At the present time, a great majority of motor vehicles are provided with internal combustion engines in which as is well known the combustion of the fuel takes place directly in the engine cylinders, practically in the form of an explosion, very high temperatures being attained. The temperatures of the various parts of the engine, however, must be kept within limits or serious consequences will follow, preventing 15 the proper operation of the engine or even leading to its serious injury. It is necessary for this purpose to provide means for cooling the engine so as to dissipate the excess of heat, the most common construction for this 20 purpose consisting of a water circulation cooling system. As usually employed this system comprises a series of water jackets about the engine cylinders and a radiator connected with the water jackets, a circulation 25 of the cooling water being maintained through the cylinder jackets and radiator by means of a pump or by gravity as in the well-known thermo-siphon systems. The water enters the jackets at one point usually 30 at the lower end, circulates around the cylinders and passes out through the return pipe which conveys the water to the radiator. The water then passes through the radiator where it is cooled and then is re- 35 turned to the cylinder jackets through the inlet pipe. Any overheating of the engine quickly results in raising the temperature of the circulating water, particularly the water leaving the jackets and the temper- 40 ature of the cooling water at this point, therefore, forms an index of the thermal condition of the engine.

Overheating may result from a variety of causes such as insufficient lubrication of the 45 cylinders, resulting in friction between the pistons and cylinders, which places an excessive load on the engine causing it to heat; insufficient lubrication of the bearings producing like results; too rich a mixture of fuel and air which produces an excessively

high temperature of combustion; insufficiency of the cooling system; stoppage in the circulation of the cooling water, either from some obstruction or breakage of the 60 circulating pump; deficiency of the water in the cooling system; or defective circulation of air through the radiator such as may result from the breaking or slipping of the fan belt.

Among the results which may follow from overheating are "seizing" of the pistons within the cylinders, which may also result in the breaking of the crank shaft or the cracking of a cylinder; burning out of the 65 bearings of the engine; and premature ignition owing to the high temperature within the combustion chamber. Several of the causes of overheating are progressive in their nature, such as insufficient lubrication of the cylinders or bearings, as this not only 70 results in friction which causes overheating but the overheating itself further interferes with the lubrication as by burning the oil in the cylinders which aggravates the difficulty. Unless then, the initial causes of 75 the trouble are quickly cured, serious consequences will follow, although usually if the engine is promptly stopped and the unfavorable conditions corrected, actual injury to the mechanism may be avoided. It is, 80 therefore, apparent that some means for determining the thermal condition of the engine is of the greatest value in securing the safe and proper operation thereof and further, that the desired indication of temperature 85 may be obtained by properly measuring the 90 temperature of the cooling water.

Not only is it desirable to secure an indication of excessively high temperatures in 95 internal combustion engines but it is also a great advantage to be able to guard against the temperature becoming too low. Thus in extremely cold weather, there is danger when the engine is not running of the cooling water freezing, which may result 100 in bursting the radiator or even cracking the cylinder jackets. It is also important to maintain the temperature of the engine at as high a point as is compatible with safety from overheating as a greater efficiency in 105 the use of fuel is thereby obtained and a smoother and more satisfactory operation of the engine results. For the most satisfactory operation of the engine, therefore, its temperature should be maintained as 110

high as is practicable without encountering the dangers and objections of excessive heating. In the ordinary water-cooled motor, this condition usually obtains when the temperature of the cooling water upon leaving the cylinder jackets is slightly below the boiling point. When the water is at this temperature the engine will be operated economically and satisfactorily and at the same time, the cooling water does not boil away as would be the case if the boiling point were exceeded and is thereby enabled to perform properly its cooling function. The formation of steam by the boiling of the cooling water may, therefore, be considered as indicating a condition of probable danger requiring the immediate attention of the operator.

In accordance with the present invention, I provide accurate and convenient means for indicating to the operator of the vehicle at all times the thermal condition of the engine as shown by the temperature of the cooling water and advising him at once of the reaching of a condition of boiling and steam formation.

I have found that the temperature of the water in the cylinder jackets varies greatly in different parts of the jackets, being ordinarily coolest at the lower ends where it enters and gradually becoming heated, reaching its highest temperature only after it has surrounded the hottest part of the cylinder which is adjacent to the head and exhaust valve thereof, this part of the cylinder being where the ignition of the fuel charge takes place and where the highest temperature of combustion is reached. As explained above, the condition of danger in the operation of the engine corresponds for practical purposes with a condition in which the water in the jacket boils, resulting in the formation of steam. It is highly desirable, therefore, to have an indication immediately upon the formation of steam in whatever part of the jacket this may take place. I have discovered that by providing means responsive to temperature changes and locating the same in the cooling system at or above the upper ends of the cylinders or at least as high as the combustion chambers thereof, the results desired are secured, as with this location of the temperature responsive element, it is not only subjected to the hottest water temperature, but as any steam formed immediately rises, it is also in a position to be influenced by steam formed in any part of the cylinder jacket.

In my Patent No. 1,090,776, dated March 17, 1914, I have disclosed a system and apparatus for indicating the thermal condition of an internal combustion engine embodying the use of a device having a temperature-responsive element located in the

air space above the normal level of the water in the system, as set forth in said patent. I am by these means enabled to obtain a relative indication of the temperature of the cooling water and also obtain a danger signal immediately upon the formation of steam in the system which steam passes into the air space, thus causing a sudden increase in the temperature indication of the instrument. This construction does not normally give the actual water temperature but indicates a temperature somewhat lower than that of the water until the formation of steam takes place. For many purposes, the invention of this patent is most desirable and satisfactory, but under some conditions it is preferable to indicate the actual temperature of the heated water in the system. My present invention provides means whereby this actual hot water temperature is indicated at all times and which will also be subjected to the action of any steam which may form in the system. Thus, with this invention, it is possible to secure an indication of actual water temperature without sacrificing the advantages of obtaining immediate knowledge of a condition of danger suggested by the formation of steam.

In the accompanying drawings, which form a part of this specification, and which illustrate one preferred embodiment of my invention, Figure 1 is a diagrammatic side elevation of the engine, radiator and connections, and portion of the dash of a motor vehicle showing the application of my invention thereto, a part of one cylinder being shown in section. Fig. 2 is a vertical sectional view through the indicating instrument. Fig. 3 is a front view of the instrument, parts being broken away to show the interior construction.

Referring to the drawings in detail, the numeral 1 designates an automobile engine provided with the cylinders 2 in which work the pistons 3. Each of the cylinders is surrounded by a water jacket 4, which is connected by a branch pipe 5 with the main return pipe 6. The latter discharges the water into the radiator 7 through which the water passes in small streams and is subjected to currents of air forced through the radiator by the movement of the vehicle, usually assisted by a fan 8 as is customary in motor vehicle construction. The water when cooled passes from the bottom of the radiator to the lower portions of the cylinder jackets through the inlet pipe 9 and branches 10. The circulation of the water may be maintained by any suitable means, as by means of the circulating pump 11. As the ignition and combustion or explosion of the charge takes place primarily in the upper end of the cylinders when the pistons are at or near the upper limits of their

strokes, it will be seen that these portions of the cylinders constitute combustion chambers (designated by the numeral 12) where the greatest temperature is reached. The 5 cooling water, therefore, does not reach its maximum temperature until it reaches the part of the water jacket surrounding the combustion chamber. The exhaust valves of the cylinder are also located at the upper 10 ends thereof, as is well-known and the hot gases rushing out through these valves when opened further contributes to make this part of the cylinder the hottest. Preferably, therefore, I provide means for taking the 15 temperature of the cooling water at or after it has passed this hottest region so as to get its maximum temperature.

The engine described is shown as inclosed beneath the usual hood 15, the vehicle being provided with a dash or instrument board 16 which forms a part of the vehicle body 17 and which as is customary is located immediately in front of the driver's seat so that instruments placed thereon may be 25 readily observed by the driver when operating the car.

In accordance with the present invention, I provide a device having a part responding to temperatures in the cooling system and 30 having means for indicating such temperatures located in such a way as to be under the constant observation of the driver, such indicating means being preferably located on the dash or instrument board where the 35 other instruments necessary for the operation of the car, such as the speedometer and ammeter, are customarily placed. I accomplish this result by employing means having a temperature responsive element 40 which may be located in a part of the cooling system where it will be influenced by the temperature of the cooling water, preferably after the water has reached its highest temperature or of any steam which may 45 form in the jackets, and an indicating instrument located upon the dash, of such a character that it may easily be observed by the driver; these two instrumentalities being operatively connected by means which will 50 cause the indicator to indicate the temperature to which the temperature responsive element is subjected, the operative connection being such that it will not be destroyed or affected by the decidedly severe and special 55 conditions which exist in a motor vehicle.

The construction which I have illustrated and which complies with the requirements named comprises a temperature responsive element 20 in the shape of a bulb filled with 60 an expansible fluid, this bulb being located in the cooling system preferably in such a place as to be influenced by the cooling water after it has attained its highest temperature and where it will be subjected to 65 the action of any steam which may form

in the jackets. In the specific embodiment shown the bulb is mounted in the return pipe, which conveys to the radiator the hot water leaving the upper ends of the cylinder jackets the bulb being preferably located at a 70 point in the return pipe where it will be acted upon by the flow from all the cylinders. This location of the bulb is advantageous as the temperatures of the different cylinders sometimes varies and this location 75 of the bulb insures that it will be subjected to the influence of the water coming from the hottest cylinder. This location of the bulb also insures that it will be acted upon by the steam formed in the jackets of any 80 of the cylinders. This bulb is connected by a flexible tube 21 of suitable material having a bore filled with the expansible fluid, with the indicating instrument 22, which is illustrated as being mounted on the dash 16. 85 This instrument comprises a Bourdon tube 23, with the interior of which the bore of the flexible tube communicates, the free end of the Bourdon tube being connected by suitable mechanism to the indicating member or hand 24. As illustrated the end of the tube is connected to a lever 25 fulcrumed on a pivot 26, the other end of the lever being connected to the hand. 90 The increase of temperature of the cooling water will cause the fluid in the bulb 20 to expand, which will force the column of fluid to move in the tube 21 producing an increase of pressure in the Bourdon tube 23. This increase in pressure results in accordance 95 with the well-understood mode of operation of a Bourbon tube in a tendency for the latter to straighten out causing a movement of the free end of the tube, which operates through the lever 25 to actuate the hand 24. Conversely a cooling of the water will cause the fluid in the bulb to contract thus relieving the pressure in the Bourdon tube and permitting the hand to return toward its initial 100 position. The Bourdon tube and hand are preferably inclosed in a suitable casing 30, the hand moving over a suitably divided dial plate 31. Preferably the front of the instrument is closed by a cover 32 having a window 33 therein, through which the movements of the hand over the scale may be 105 observed.

It will be understood that any desired temperature measuring and indicating means may be used employing any suitable form of temperature-responsive element or indicating devices other than such as above described.

It will be seen that with the construction described, a temperature responsive means is provided which is located in the most effective position to respond to the temperature changes which it is desired to indicate and an indicating means is also provided 125 which is located in a most convenient posi- 130

tion for observation by the driver, namely, on the instrument board or dash of the vehicle. The use of the flexible connecting tube between these two instrumentalities is most important as making this arrangement possible and as producing an operative device which shall not be subject to damage or unfavorable influence, owing to the peculiar conditions of use. These severe conditions which must be dealt with include the continuous vibration of the motor necessarily resulting from its operation, and of which vibration the temperature responsive element partakes, and the independent or secondary vibration of the instrument board or dash which it receives indirectly from the motor through the vehicle frame and body, and also the working or twisting to which the dash as a part of the vehicle body is necessarily subjected due to the strains resulting from the rapid movements of the vehicle over uneven road surfaces. The vibrations set up in various parts of the vehicle body by the engine are less acute than, and do not ordinarily correspond in amplitude and phase with the vibrations of the engine itself as they are influenced by the natural periods of vibration of the several body parts; also as the vehicle frame and body cannot be made absolutely rigid, the strains incident to movements of the vehicle necessarily result in the relative movement of the various parts of the vehicle. Thus it will be seen there is a tendency to constant relative displacement of more or less extent between the dash or any part of the vehicle body and the engine. The use of the flexible tube compensates for all of these movements and permits them to take place without destroying the responsive nature of the operative connection between the temperature responsive element and the indicating instrument. Furthermore, in an instrument of the character described, the Bourdon tube and hand are necessarily of more or less light or fragile construction and unable to withstand continuous sharp vibrations such as are produced in the motor itself and in fact such vibrations would tend to make accurate reading of the instrument impossible as the hand would be continually in motion. Therefore, it is important that the direct and sharp vibrations of the motor be not positively transmitted to the indicating instrument as through a rigid, metallic connection. The use of a flexible tube prevents this and permits the instrument to indicate accurately as the vibrations and movements to which it is subjected indirectly through the vehicle body are of a different character from those emanating directly from the engine and are not such as to prevent its satisfactory operation. The use of the flexible tube also permits the location of the temperature re-

sponsive element in such part of the cooling system as is most desirable to produce temperature indication which is most responsive to the thermal conditions of the engine and it also permits the same type of instrument to be adapted to attachment to vehicles of various constructions making a standard form of device available.

The location of the temperature responsive element in the upper part of the cooling system or at least as high as the combustion chambers of the cylinders is important as it insures that the instrument shall respond to maximum temperatures existing in the system and not to some lower temperature. Obviously a condition of danger is suggested if the boiling point is reached in any part of the system and the maximum temperature of the water in the system should, therefore, govern the indication. This is accomplished by my invention by locating the temperature responsive element in the upper part of the system as it will there be subjected to the water after it has reached the hottest part of the cylinder and it will also be subjected to steam formed in any part of the jacket as such steam will immediately rise and so necessarily reach the temperature responsive element.

The location of the indicating instrument in a position near to the driver such as on the dash or instrument board has particular utility in connection with devices indicating the actual temperature of the cooling water for the reason that the changes in the temperature of the water are more or less gradual and consequently the indications of the instrument vary more or less gradually up to and including the danger point indicated by the temperature of boiling. This continuous temperature change indication must, therefore, be observed by the driver and this can best be accomplished when the indicating instrument is located in convenient proximity to him.

The Bourdon tube type of instrument described is particularly well fitted to the purposes of the present invention as the movement of the indicating hand produced by the operation of the Bourdon tube of this construction naturally has a very open scale in the upper ranges of its movement; that is to say at the high temperatures and at or near the danger point relatively small changes of temperature will produce considerable movements in the indicating hand, thus making the instrument very easy to read at this point and producing the effect of a warning signal directing the operator's attention to the approach of dangerous conditions of operation.

While I have referred specifically to automobiles in the foregoing description it will be understood that somewhat similar

conditions prevail in the case of other motor vehicles provided with internal combustion engines. My invention, it will be seen therefore, is applicable in connection with vehicles of various types and is not to be understood as limited to automobiles or vehicles adapted to travel only on the surface of the earth but is of general application to internal combustion vehicle propelling motors.

While I have shown and described one preferred embodiment of my invention, it will be understood that various changes in the location and construction of the parts may be employed and I do not, therefore, desire to limit myself to the embodiment shown, but intend to cover my invention broadly in whatever form its principle may be embodied.

This case is a division of my application Serial No. 846,247, filed June 20th, 1914.

Having thus described my invention, I claim:

1. In temperature indicating means for water-cooled internal combustion motors of motor vehicles, the combination with the water circulation cooling system, of a temperature responsive element located in a position to be influenced by the temperature of the cooling liquid on its way to the radiator after it has been affected by the temperature of the combustion chamber of a cylinder, an indicating instrument located in a position to be observed by the driver when operating the vehicle and an operative connection between the temperature responsive element and the indicating instrument.

2. In temperature indicating means for water cooled internal combustion motors of motor vehicles, the combination with a motor and the water circulation cooling system thereof, of a temperature-responsive element located in said system above the level of the hottest part of a motor cylinder, and in a position to be normally in contact with the cooling liquid after it has been heated by such hottest part, and to be subjected to contact with any steam which may be generated in the system due to the heat in the cylinder, and temperature-indicating means observable by the driver when operating the vehicle, said temperature indicating means being controlled by the temperature of said temperature-responsive element.

3. In a temperature indicating means for multiple cylinder internal combustion vehicle propelling motors, having a water circulation cooling system including a plurality of cylinder jackets, a radiator, and a return pipe for conveying the heated water from a plurality of said jackets to said radiator, the combination with said return

pipe, of a temperature-responsive element located in a part of said return pipe where it will be influenced by the temperature of the water coming from a plurality of said jackets, and means controlled by said element and observable by the driver when operating the vehicle for indicating changes in the temperature of said element.

4. In temperature indicating means for multiple cylinder internal combustion vehicle propelling motors having a water circulation cooling system, including a plurality of cylinder jackets, a radiator, and a return pipe connecting the upper ends of the cylinder jackets with the radiator, the combination with said return pipe, of a temperature responsive element located in said return pipe between said cylinder jackets and said radiator, said temperature-responsive element being at a higher level than the upper ends of said cylinder jackets, and means controlled by said element and observable by the driver when operating the vehicle for indicating changes in the temperature of said element.

5. In temperature indicating means for internal combustion vehicle propelling motors having a water circulation cooling system in which the water circulation is upward in the cylinder jackets and leaves the jackets at the upper ends thereof, the combination with the cooling system, of a bulb immersed in the circulating water in the upper portion of the system where it will be subjected to contact with steam formed in any part of a jacket and to the temperature of the water after it has reached the hottest part of the cylinder, an indicating instrument located on the vehicle dash and comprising a pressure responsive element and an indicating member, a flexible tube connecting the bulb and pressure responsive element, and an expansible fluid filling the bulb and flexible tube.

6. In temperature indicating means for multiple cylinder internal combustion vehicle propelling motors having a water circulation cooling system, including a plurality of cylinder jackets, a radiator, and a return pipe for conveying the hot water from the upper parts of the jackets to the radiator, the combination with the cooling system of a bulb located in said return pipe where it will be influenced by the hot water or steam coming from a plurality of said cylinder jackets, an indicating instrument located on the vehicle dash and comprising a pressure responsive element and indicating means, a flexible tube connecting the bulb and pressure responsive element and an expansible fluid filling the bulb and flexible tube.

HARRISON H. BOYCE.
